2 SHEETS—SHEET 2.

UNITED STATES PATENT OFFICE.

WILLIAM K. ANDERSON, OF WORDEN, ILLINOIS.

AUTOMATIC MINE-CAR STOP AND RELEASE.

1,176,123.

Specification of Letters Patent. Patented Mar. 21, 1916.

Application filed September 15, 1913. Serial No. 789,867.

To all whom it may concern:

Be it known that I, WILLIAM K. ANDERSON, a citizen of the United States, and resident of Worden, Madison county, Illinois, have invented certain new and useful Improvements in Automatic Mine-Car Stops and Releases, of which the following is a specification containing a full, clear, and exact description, reference being had to the accompanying drawings, forming a part hereof.

My invention relates to improvements in automatic mine car stops and releases, and the object of my invention is to construct an improved automatic car stop and release carried solely by a mine cage, and wherein the act of stopping and releasing a car is brought about solely by the cage and a car entering the cage.

With the above purposes in view my invention consists in certain novel features of construction and arrangement of parts as will be hereinafter more fully described, pointed out in the claims and illustrated by the accompanying drawings, in which—

Figure 1 is an elevation illustrating an apparatus for stopping and releasing mine cars constructed according to my invention; Fig. 2 is a fragmental end elevation; and

Fig. 3 is a plan illustrating my invention.

Referring by numerals to the accompanying drawings: 5 designates the cage having the rails 6 thereon.

7 designates a track-way located in an entry (not shown) communicating with the shaft (not shown) in which the cage 5 operates.

The form of cage shown is a "dumping" cage, and in its specific construction and relative arrangement with the track-way 7 is common and forms no part of my invention.

8 designates an ordinary mine car having the ordinary flanged wheels 9 for riding over the rails 6 and 7 which wheels are mounted upon the ordinary axles 10.

11—11 designates elongated bearing-plates which are secured to the platform of the cage 5 parallel and preferably between the rails 6.

12 designates car stops in the form of arms having hooks at their ends. These stops 12 are arranged in oppositely disposed pairs and each pair is pivotally secured to the bearing-plates 11.

13 designates guides for the outer free ends of the plates 21 and 40, and 14 designates extensible coil springs for normally holding the plates elevated, so that the stops 12 will be normally in positions to engage the axles of the cars.

15 designates a hanger depending from the platform of the cage and arranged for the support of a pivoted arm 16. Carried at one end of the arm 16 is a dog 17 which is pivotally carried by the arm. This dog is located adjacent the receiving end of the cage. At the other end of the arm 16 there is a spring 18 and extending upwardly from the free end of said spring is a rod 19 which is adjustable as to length by means of a turn-buckle 20. This rod is connected with the plate 21 so that when the arm 16 is operated upon a movement of the cage, as will be more fully explained hereinafter, the plate will be drawn downwardly and the forward pair of stops 12 will be released from the forward axles of the car.

The forward pair of stops 12 are mounted upon rods 22 arranged to ride in slots 23 in the bearing-plates 11, whereby when the act of stopping a car takes place the said stops may have a limited movement with the car.

24 designates a draw-bar secured to the rod 22 at its one end and to a retractile coil spring 25 at its other end which means serves as a cushion for the stopping of the cars on the cage.

26 designates a piston rod having a pivotal connection 27 with the plate 21 which supports the two forward stops. Secured to the opposite end of the piston rod 26 is a piston 28 arranged for movement in a dash-pot 29 provided with a slow-leak valve 30 and an intake valve 31. This means operates as a cushioning device auxiliary to the cushioning device previously described comprising the spring 25.

Secured in the path of travel of the dog 17 is a plate 32 which is pivotally supported in a bearing 33. This plate 32 is mounted in such manner as to have a limited downward movement at its free end so as to act as a catch for said dog when the cage descends, and the plate is hinged so that when the dog moves beneath said plate the plate may be moved automatically out of the path of the dog, so that the dog may ascend with the cage.

34 designates a shaft which is rotatably mounted beneath the cage platform. Arranged on said shaft in alinement with the dog 17 is a bell-crank 35, having a counter-

balance 36. Connecting the arm of the bell-crank 35 provided with the counterbalance 36 and the dog 17 is a rod 37, and connected with the shaft 34 vertically alining with the 5 rails 6 are the levers 38. The free ends of the levers 38 extend into the path of the mine car wheels and the balls of the rails 6 are notched at 39 to provide for the movement of said levers. By reason of the counterbalance 36 the levers 38 are each held in their operative positions and the rod 37 holds the dog 17 in a position to engage the plate 32.

40 designates a plate which supports the 15 rear stops, and secured to said plate is a rod 41 which extends downwardly through an opening formed in the platform of the cage. Beneath the cage platform the rod 41 connects with the lever 42 which is pivotally secured to a bearing 43 depending from the cage platform. At the free end of the 20 lever 42 there is secured a pedal 44 which extends upwardly through the cage platform. The stem of the said pedal is provided with ratchet teeth 45 and secured to the platform adjacent said stem is a plate 46 arranged to be engaged by the teeth of said pedal, whereby when the pedal is depressed said teeth and said plate will serve 25 to hold the lever 42 downwardly. By this means the car held by the stops on the cage may be released from said stops in a direction opposed to the ordinary release, as is required at times at the mine surface. It 30 is to be observed that the lever 42 extends diagonally relative to the cage and that the pedal 44 is located to one side of the median line of the cage, so as to be removed laterally from the bumpers of the mine cars, 35 where it will be conveniently accessible.

In the practical operation of the apparatus assuming all of the parts thereof to be in the position shown in Fig. 1, which is the 40 position of parts at a time when an empty 45 car is being lowered into the shaft after having been to the surface and dumped, the dog 17 will first engage with the plate 32 to tilt the lever 16 which in turn, by reason of the rod 19 and plate 21, will draw downwardly on the plate 21 and the forward pair 50 of stops 12, will be released by gravity from the forward axle of the car so that, when the cage has reached its downward limit of movement and the rails thereon are in the 55 same plane as the rails 7 in an entrv, the car standing on the cage will be fully released. At this time a car on the rails 7 is moved to engage the car on the cage and force it off of the cage. In the movement 60 of said second car, which is a filled car, the

levers 38 are engaged by the wheels of the second car and through the bell-crank 35 and rod 37 the dog 17 is released from the plate 32, thereby causing the springs 14 to move the stops 12 in positions to engage the 65 axles of the second or full car. After the full car has passed the levers 38 the counterbalance 36 acts to reset said levers and therewith the dog 17 to their initial positions.

It is to be particularly observed that the cars are released from the cage by a means carried solely by the cage, thus doing away with the building of release devices in the 70 entries.

I claim:

1. In an automatic mine car stop and release, the combination with a mine cage of a mechanism carried solely by the mine cage and comprising a pair of oppositely disposed car stops arranged longitudinally of the cage, a pivotal support on the cage for each of said stops, slotted bearings for one of said pivotal supports, means for holding the free ends of said stops elevated, 80 a pivoted lever, means at one end of said lever for operating one of said stop holding means, means at the opposite end of said lever for engagement with an element projecting into the mine shaft, and means comprising an element arranged in the path of the mine cars on said cage for releasing the 85 means carried by said lever engaging said fixed element in the mine shaft.

2. An automatic mine car stop and release, comprising oppositely arranged pairs of car stops, means for pivotally supporting said stops, means for normally holding said stops in positions to engage mine cars, a platform having rails thereon for the support of said cars, a lever pivotally secured to said platform, means connected with one end of said lever for operating a pair of said stops, a dog carried by the opposite end of said lever for engagement with a fixed 95 element whereby, upon the descent of said platform, the lever will be tilted and a pair of said stops released from the car, and means comprising an element arranged to be moved by a second car for releasing said 100 dog from said fixed element so that the lever and stops may be restored to positions for engagement with a car.

In testimony whereof, I have signed my name to this specification, in presence of 115 two subscribing witnesses.

WILLIAM K. ANDERSON.
